UNITED STATES PATENT OFFICE.

JOHN B. ZORN, OF KANSAS CITY, MISSOURI, ASSIGNOR OF ONE-HALF TO ANNA L. FISHER, OF KANSAS CITY, MISSOURI.

GARMENT HANGER.

Application filed February 24, 1922. Serial No. 538,850.

To all whom it may concern:

Be it known that I, JOHN B. ZORN, a citizen of the United States, residing at Kansas City, in the county of Jackson and State 5 of Missouri, have invented certain new and useful Improvements in Garment Hangers; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to garment hangers and it is particularly designed for supporting open yoke or low necked dresses and particularly of the type in which the fastening is at the shoulder.

20 Where the open portions of the yokes are relatively low and wide, the shoulders frequently slide off the ends of the dress hanger so that the dress is precipitated to the floor where it is liable to be tramped 25 upon and ruined. Particularly is this the case where garments are displayed in stores and the like.

My invention contemplates the provision 30 of means whereby dresses will be properly held upon the hangers and to this end the invention consists of a dress supporting bar and a clamping bar, one movable with respect to the other, the movable member being resiliently secured in place so that it 35 can be moved with respect to the other member to destroy the clamping engagement between the two members.

The novel arrangement of the invention 40 will be specifically described hereinafter, reference being had to the accompanying drawings, in which

Fig. 1 is a perspective view of a hanger constructed in accordance with my invention.

45 Fig. 2 is a view partly in elevation and partly in section, the clamping bar being shown in non-clamping position in full lines and in dotted lines as tilted so that one end is in clamping position.

50 Fig. 3 is an elevational view of the hanger, showing the clamping bar in clamping position, and

Fig. 4 is a cross sectional view on the line 4-4 of Fig. 3.

The dress supporting bar 1 is preferably 55 curved in the usual way common to dress hangers and it is provided with a supporting hook consisting of a strand bent intermediate its ends as at 2 to provide a hook portion and having depending clamping bar 60 guides or side bars 3 and 4, the ends of which extend through the bar 1 and are bent back upon themselves to form hooks 5 and 6, which can be secured to the bar 1, as clearly shown in Figs. 2 and 3. 65

The guide bars 3 and 4 are curved inwardly, one toward the other, intermediate their ends, as indicated at 7 and 8, and slideable on the bars 3 and 4 is a garment clamping bar 9 having openings 10 and 11 70 through which the bars 3 and 4 project.

The ends of the clamping bar 9 are preferably provided with rubber contact projections 12 and 13, adapted to bear upon the upper surface 14 of the bar 1. 75

The hook 2 is formed of a double strand by bending the wire back upon itself and there is a tension portion 15 for the side bars 3 and 4. For example, when the clamping bar 9 is in the position shown in Fig. 2, 80 the inner portions of the side bars 3 and 4 will frictionally engage the inner edges of the openings 10 and 11 so that the bar 9 will be held in non-clamping position. When it is desired to clamp the garment to 85 the bar 1, the bar 9 can be moved downwardly and since the intermediate portions 7 and 8 are bent one toward the other, the bar 9 will quickly drop until it has nearly reached its clamping position, when the frictionally 90 engaging portions 16 and 17 of the bars 3 and 4 will again begin to bind against the inner edges of the openings 10 and 11. Since there is a tensioning portion 15, the binding 95 of the inner portions of the openings 10 and 11 against the friction portions 7 and 8 will tend to spread the bars 3 and 4 apart, the tension coming at 15 but really resulting from the double strand hook 2.

Since the clamping bar 9 may be made of 100 yielding or resilient material, the operator can press the center portion of the bar 9 comparatively close to the bar 1 so as to spread the clamping projections 12 and 13 105 slightly apart and at the same time, tend to open or spread apart the bars 3 and 4. Therefore, the clamping bar will be held rigid with respect to the rest of the device

and the projections 12 and 13 will efficiently hold the garment against accidental displacement.

When it is desired to take off the garment, the bar 9 can be raised to the position shown in Fig. 2, there being sufficient friction caused by the upper portions of the bars 3 and 4 to hold it there.

For convenience and whenever desired, the bar 9 can be tilted, as shown in dotted lines in Fig. 2, so that after one shoulder of the garment is placed upon the bar 1, one of the engaging projections 12 or 13 will bind against it. Then the other shoulder may be put over the bar 1, whereupon the clamp can be brought down to clamping position, as shown in Figs. 1 and 3.

It will be observed that the device can be inexpensively manufactured, that it is easy to operate and that it will efficiently prevent the garment from accidental removal from the hanger.

What I claim and desire to secure by Letters Patent is:

1. A garment hanger comprising a garment supporting bar, a hook-shaped mem-

ber, spaced guide members connected to the hook-shaped member and having inherent tendency to resist spreading, and a clamping bar on the guides movable into clamping position to spread the guides and movable out of clamping position to permit the guides to spring back to place.

2. A garment hanger comprising a garment-supporting bar, a hook-shaped member, spaced guide members connected to the hook-shaped member and curved one toward the other intermediate their ends, and a clamping bar having elongated slots through which the guide members project, the edges of the slots being frictionally engaged by the guides so that the clamping bar can be raised on the guides above the curved portions to hold it in spaced relation with the garment supporting bar and whereby the clamping member can be moved below the curved portions of the guide members to permit it to serve as a clamp complementary to the supporting bar to hold a garment thereon.

In testimony whereof I affix my signature.

JOHN B. ZORN.
